SHELL CONSTRUCTION

Filed Feb. 6, 1930

UNITED STATES PATENT OFFICE

ARVID E. NISSEN, OF UPPER DARBY, PENNSYLVANIA

SHELL CONSTRUCTION

Application filed February 6, 1930. Serial No. 426,390.

(GRANTED UNDER THE ACT OF MARCH 3, 1883, AS AMENDED APRIL 30, 1928; 370 O. G. 757)

This invention described herein may be manufactured and used by or for the Government for Government purposes, without the payment to me of any royalty thereon.

6 This invention relates in general to projectiles and more particularly has reference to a construction of a shell for firing from rifled muzzle loading mortars.

Previous to this time shells for firing from 10 weapons of this character have been provided with an expandible band for engaging the rifling on firing of the propellant charge. It will be appreciated that it is necessary to employ an expandible band, inasmuch as a rifle band necessarily being of greater diameter than the projectile to which it is attached, can not be conveniently loaded in a muzzle loading weapon.

An essential feature of the construction is 20 the prevention of relative rotation between a projectile and the band attached thereto, as otherwise the desired rotation of the shell would not result. In the past, expandible bands have been positively fastened to the 25 base of a shell by screws.

While this fastening arrangement is sufficient as regards preventing relative rotation, it is attended by the disadvantage of materially adding to the cost of shell construction, and tends to weaken the structure thereof, inasmuch as it is required to drill and tap the shell base and drill the band for the insertion of the screws.

An object of this invention is to provide a 35 projectile having an expandible band loosely fitted thereon, adapted to become attached thereto on firing.

Another object of this invention is to provide a projectile having an expandible band 40 loosely fitted thereon, adapted to become attached thereto on firing by reason of engaging portions formed on the base of the projectile.

Another object of this invention is to provide a projectile having an expandible band 45 loosely fitted thereon, adapted to become attached thereto on firing by reason of engaging portions formed on the base of a band adjacent the projectile.

50 Still another object of this invention is to

provide a projectile having an expandible band loosely fitted thereon, adapted to become attached thereto on firing by reason of corresponding engaging portions formed on the base of the projectile and the adjacent 55 face of the band.

A further object of this invention is to provide a projectile having an expandible band loosely fitted thereon, adapted to become attached thereto on firing by reason of engaging 60 portions formed on the face of the band adjacent the base of the projectile, which latter is formed of soft metal.

With these and other objects in view which may be incident to my improvements, the invention consists in the parts and combinations to be hereinafter set forth and claimed, with the understanding that the several necessary elements comprising my invention, 65 may be varied in construction, proportions and arrangement, without departing from the spirit and scope of the appended claims.

In order to make my invention more clearly understood, I have shown in the accompanying drawings means for carrying the 70 same into practical effect, without limiting the improvements in their useful applications to the particular constructions, which for the purpose of explanation, have been 75 made the subject of illustration.

In the drawings forming a part of the specification, Figure 1 is a longitudinal sectional view of the base of a projectile forming the subject matter of this invention showing the knurled base.

Figure 2 is a bottom view of the base of a projectile also showing the knurling.

Figure 3 is a longitudinal sectional view of the projectile shown with the expandible band fitted on the base thereof against the 80 knurling.

Figure 4 is a plan view looking towards the base of a modified form of cupped disc.

Referring more particularly by numerals 95 to the drawings wherein similar elements are designated by like symbols of reference throughout, and more especially to Figure 1, there is shown a rear of a projectile 1 having side walls 2 integrally formed with a base portion 3. A reduced threaded exten- 100

sion 4 is centrally formed on the rear of the base portion adapted to receive a cartridge container 5, as shown in Figure 3.

The foregoing description is applicable to the type of shell now employed in rifled muzzle loading mortars. In accordance with my invention, however, I machine or otherwise form an annular rim 6 concentric with the base of a projectile and of the same diameter, 10 being flush with the integral side walls 2. The surface of the rim 6 is knurled, as shown in Figure 2, or otherwise provided with a surface capable of engaging in soft metal.

An expandable cupped disc 7 is adapted to 15 be fitted against the knurled portion 6 on the base of the projectile and held on the extension 4. The expandable cupped disc, as shown in Figure 3, is of a character heretofore employed, consisting essentially of a cupped annular plate having central apertures for receiving the extension 4 on the base of the projectile. One face of the plate is provided with a concentric annular groove 10 adjacent the edge which is bent outward at this 20 point as at 8, and extends downwardly, flush with the periphery of the shell body.

The inner edge of the downwardly bent portion 8 is tapered to seat the edge of a pressure plate 9 formed with angularly extending edges 11 and 12, the edge 11 resting on the tapered portion of the downwardly turned edge 8 of the expandable cupped disc and the edge 12 being tapered at the end to rest on the inner edge of the cupped disc 35 which is bent downwardly as at 13.

A cartridge container 5 internally threaded at one end is adapted to be inserted in the apertures provided in the pressure plate and an expandable cupped disc, and screwed 40 on the extension 4. The end of the container 5 internally threaded, is reduced in diameter at the end to provide a shoulder 14 adapted to fit against the inner edge 12 of the pressure plate, and holds the plate and 45 cupped disc against the base of the projectile.

The cartridge container is provided in addition with a series of apertures 15 affording an outlet to the gas generated by ignition of the cartridge contained therein, not shown, 50 adapted to fire the propellant charges contained in the powder disc, not shown, adapted to be carried on the outside of the container 5.

While the shoulder 14 on the container 5 is adapted to hold the cupped disc 7 in place by engagement with the pressure plate 9, it will be appreciated that the fastener is not sufficient to prevent relative rotation of the band and the projectile, in the absence of 55 positive fastening means therebetween, which have been previously employed, screws having been used as hereinbefore explained.

In accordance with my invention the knurled surface 6 formed on the base of the 60 projectile is adapted to be positively engaged

by the cupped disc on firing of the projectile and to prevent relative rotation therebetween. The cupped disc engages the rifling in the barrel and imparts the desired rotation to the projectile. The expandable band 70 should be constructed of metal sufficiently strong to withstand buckling deformation which might prevent firm engagement with the base of the cupped disc 7 and the knurled portion 6. The knurling in the shell base 75 may be varied in amount of depth or width, or any suitable provision for the engagement by the band, substituted therefor.

The base of the projectile may be constructed of soft metal and the adjacent face of the cupped disc provided with a knurled surface adapted to engage the same, as disclosed by the cupped disc 7' shown in Figure 4. This disc, as may be observed, is provided with knurled portions 16 adapted to seat upon the base of the projectile. It will thus be seen that either or both the base of the projectile and adjacent face of the disc may be knurled and such constructions employed with advantage when practicing my invention. 80 85 90

The operation of the invention may readily be understood with reference to Figure 3, wherein on firing, the force exerted by the propelling charge will drive the pressure plate 9 forward, causing it to straighten and expand, and driving the edge 8 of the cupped disc outward into the rifling, which bending is facilitated by reason of the groove 10 providing a weakened portion to facilitate bending. Concomitantly with the expansion of the edge of the cupped disc into the rifling, the disc is driven forward into the knurled portion formed on the base of the projectile, where the same is positively engaged therebetween, and relative rotation between the band and the projectile thus prevented. 95 100 105

There is accomplished by this invention, a projectile construction having shells adapted to be fired from rifled muzzle loading mortars 110 wherein relative rotation between the driving disc and the projectile is positively prevented, and the use of fastening means heretofore required dispensed with, thus providing a shell which is of stronger construction 115 and which may be more rapidly and economically manufactured than the projectiles heretofore used.

While I have shown and described the preferred embodiment of my invention, I 120 wish it to be understood that I do not confine myself to the precise details of construction herein set forth, by way of illustration, as it is apparent that many changes and variations may be made therein, by those skilled 125 in the art, without departing from the spirit of the invention, or exceeding the scope of the appended claims.

I claim:

1. A projectile for firing in a rifled barrel 130

- comprising a body portion, and a disc loosely carried thereon, and means associated with the disc to attach the same to the body portion so as to prevent its relative rotation with respect thereto on the firing of the projectile.
- 5 2. A projectile for firing in a rifled barrel comprising a body portion, an expansible disc loosely carried on the rear thereof, and means formed thereon adapted to cooperate with means formed on the body portion to attach the disc to the latter so as to prevent its relative rotation with respect to the body portion on firing of the projectile.
- 10 3. A projectile for firing in a rifled barrel comprising a body portion, an expansible disc carried on the rear thereof, and means formed thereon adapted to cooperate with corresponding means formed on the adjacent face of the body portion to attach the disc thereto so as to cause it to rotate therewith on firing of the projectile.
- 15 4. A projectile for firing in a rifled barrel comprising a body portion, an extension of reduced diameter associated with the base of the body portion containing a propellant charge, an expansible cupped disc loosely carried on the extension adjacent the base of the body portion and forward of the propellant charge, and a knurled portion integrally formed with the base of the body portion to engage the adjacent face of the cupped disc and attach the same thereto so as to prevent the relative rotation of the cupped disc with respect to the body portion on the firing of the projectile.
- 20 5. A projectile for firing in a rifled barrel comprising a body portion, an extension of reduced diameter associated with the base of the body portion containing a propellant charge, an expansible cupped disc loosely carried on the extension adjacent the base of the body portion and forward of the propellant charge, and corresponding knurled portions formed on the base of the body portion and the adjacent face of the band adapted to engage and fix the cupped disc to the base of the body portion so as to prevent rotation therebetween on the firing of the projectile.
- 25 6. A projectile for firing in a rifled barrel comprising a body portion, a cupped disc loosely carried thereon, an expansible plate positioned upon said disc, and means associated with the disc to attach the same to the body portion so as to prevent its relative rotation with respect thereto, on the firing of the projectile.
- 30 7. A projectile for firing in a rifled barrel comprising a body portion, a cupped disc loosely carried thereon, an expansible plate positioned upon said disc and means associated with the plate for expanding the same and engaging the disc with the rifling and 65 for fixing the disc to the body portion so as to cause it to rotate therewith upon the firing of the projectile.
8. A projectile for firing in a rifled barrel comprising a body portion, an extension of reduced diameter associated with the base of the body portion containing a propellant charge, an expansible cupped disc loosely carried on the extension adjacent the band of the body portion and forward of the propellant charge, an expansible plate positioned upon the cupped disc, said extension engaging said plate, a knurled portion formed on the base of the body portion and adjacent the face of the cupped disc adapted to engage and fix the disc to the base of the body portion on the firing of the projectile.
- 70 80 85 90 95 100 105 110 115 120 125 130
- In testimony whereof I affix my signature.
- ARVID E. NISSEN.
